(57) **CLAIM**

The ornamental design for a toy paper press, as shown and described.

DESCRIPTION

FIG. 1 is a front elevational view of the toy paper press, showing the new design;

FIG. 2 is a rear elevational view thereof;

FIG. 3 is a left-side elevational view thereof;

FIG. 4 is a right-side elevational view thereof;

FIG. 5 is a top plan view thereof;

FIG. 6 is a bottom plan view thereof;

FIG. 7 is a front, right-side, top perspective view thereof;

FIG. 8 is a rear, left-side, bottom perspective view thereof;

FIG. 9 is a front elevational cross-sectional view taken along line 9-9 in FIG. 5; and,

FIG. 10 is a front, right-side, top perspective cross-sectional view taken along line 10-10 in FIG. 1.

The broken lines depict parts of the toy paper press that form no part of the claimed design.

1 Claim, 10 Drawing Sheets
